UNITED STATES PATENT OFFICE.

EUSTACE CREEES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS OR SIMILAR ARTICLES.

SPECIFICATION forming part of Design No. 35,995, dated August 12, 1902.

Application filed June 20, 1902. Serial No. 112,554. Term of patent 7 years.

To all whom it may concern:

Be it known that we, EUSTACE CREEES and CHARLES S. COURT, citizens of the United States, residing at Providence, in the county of Providence and State of Rhode Island, have invented and produced a certain new, original, and ornamental Design for the Handle of a Spoon or Similar Article, (Case B,) of which the following is a specification, reference being had to the accompanying drawings, forming part thereof.

Figure 1 is a face view of our new design as embodied in the handle of a spoon, and Fig. 2 a rear view of the same.

As shown in the drawings, the leading or material feature of our design consists in the representation in relief of water-lilies and leaves. In detail it is as follows: The handle consists of a head A, an adjacent swelled portion B, and a stem C. The representation of a water-lily *a* with surrounding leaves *b*, *c*, and *d* form the head ornamentation. The leaf *d* above the lily is folded to form a pointed termination of the head. The swelled portion B has thereon the representation of a water-lily *e* overlying leaves *f*. The beading is formed by representations of lily-stems. One marginal bead is formed by the stem *g*

of a lily-bud *h*, terminating at the base of the head A. The stem C of the handle is ornamented by a lily-bud *i*, surmounted by a cluster of leaves *j*, whose stem *m* forms a portion of the marginal beading. At the base of the stem is a leaf-cluster *n*.

The rear of the spoon-handle is provided with a marginal beading of slender leaves *k*, which slightly radiate as they proceed from the base to the head of the handle, where they terminate.

It is evident that our design is applicable to the handles of articles other than but similar to those of spoons.

Having described our invention, what we claim as new, and desire to secure by Letters Patent, is—

The ornamental design for the handle of a spoon or similar article, as herein shown and described.

In testimony whereof we have affixed our signatures in presence of two witnesses.

EUSTACE CREEES.
CHARLES S. COURT.
